BEAM TUBE SWITCHING CIRCUITS

Frederick E. Zogg, Ontario, N. Y., assignor to Burroughs Corporation, Detroit, Mich., a corporation of Michigan

Application January 23, 1958, Serial No. 710,651

7 Claims. (Cl. 315—21)

This invention relates generally to multi-position electron beam switching tubes and to systems for clearing an electron beam from a position in the tube and resetting the beam in a selected "0" position.

One type of multi-position electron beam switching tube, to which the principles of the invention apply, is described in U. S. Patent No. 2,721,955 of Fan et al. This type of tube includes a central cathode which is surrounded by a plurality of groups of electrodes, each group representing a position at which an electron beam may be formed. Each group of electrodes includes a target electrode for receiving an electron beam and developing an output signal therefrom, and a spade electrode adapted to form and hold an electron beam on its associated target electrode. Each group of electrodes may also include a switching electrode for switching an electron beam from one group of electrodes to the next under the influence of crossed electric and magnetic fields.

Generally, in the operation of a tube of this type, with all of the tube electrodes carrying their normal supply voltages, electrons emitted by the cathode are retained in the vicinity of the cathode, and an electron beam does not form in any of the tube positions. When a spade or switching electrode has its electrical potential suitably reduced, the electric field pattern is altered and an electron beam forms on a target electrode associated with that spade or switching electrode. Ordinarily, the electron beam thus formed may be moved from one position to the next by means of suitable electrical pulses applied to the switching electrodes.

In some applications of these tubes, for example in decade counters or the like, it is desirable to be able to allow the tube to execute a predetermined counting operation, that is, to move from position to position until it reaches a predetermined position and then to clear the tube and reset the electron beam at a selected "0" position. Circuits are known for clearing and resetting tubes of the type described above, and, although these known circuits are generally satisfactory, they are characterized by comparatively low speed of operation.

Accordingly, one object of the present invention is to provide an improved circuit for clearing and resetting an electron beam in a multiposition electron tube.

Another object of the invention is to provide an improved high speed circuit for clearing and resetting an electron beam in a multi-position electron tube.

The present invention is particularly applicable to the above-described type of multi-position electron beam tube. In the circuitry associated with such a tube, generally, the target electrodes are connected to a target buss through which supply voltage is provided. Similarly, the spade electrodes are connected to a spade buss through which supply voltage is provided for the spade electrodes. According to the invention, means are provided coupled directly to the spade buss, for reducing the potentials of all of the spade electrodes to such a level that an electron beam cannot be held on any target

2

electrode. This operation clears the tube of an electron beam which might have been flowing to one of the target electrodes. Subsequently, the potentials of the spade buss and the spade electrodes are allowed to rise rapidly toward their normal operating levels. However, the potential of the spade electrode at the selected "0" position, at which it is desired to re-set or re-form the electron beam, rises slowly so that this "0" spade carries a lower electrical potential than the other spades and 10 the electron beam forms at the "0" position.

The invention is described in greater detail by reference to the single sheet of drawings wherein:

Fig. 1 is a perspective view of an electron beam switching tube of a type with which the principles of 15 the invention may be employed; and

Fig. 2 is a schematic representation of the tube of Fig. 1 and a circuit in which it may be operated.

The invention is described below as it applies to a multi-position electron beam tube of the type shown in 20 U. S. Patent No. 2,721,955 to Fan et al. This type of tube 10 is shown in Fig. 1 and includes, briefly, an envelope 12 which contains a central longitudinally elongated cathode 14 and ten groups of electrodes spaced 25 radially from the cathode and surrounding the cathode. Each group of electrodes includes a generally U-shaped elongated spade electrode 16 and a target electrode 18 positioned so that each target occupies the space between adjacent spade electrodes. Each spade electrode serves 30 to form and hold an electron beam on its associated target electrode. A generally rod-like switching electrode 20 is also included in each group of electrodes and is positioned between one edge of each target electrode and the adjacent spade electrode. An open-ended cylindrical permanent magnet 22 is provided surrounding 35 the tube envelope and coaxial therewith. The magnet provides an axial magnetic field which is utilized in conjunction with electric fields within the tube to form and switch an electron beam from the cathode to each of the groups of electrodes.

40 Briefly, in operation of tube 10, electrons emitted by the cathode are retained at the cathode if each of the spades, targets and switching electrodes carries its normal operating electrical potential. When a spade or switching electrode experiences an appropriate reduction in potential, an electron beam is formed and directed to a target electrode. The electron beam is switched from one target electrode to the next by thus suitably altering the electrical potentials of a spade or switching electrode.

45 A circuit embodying the invention is shown in Fig. 2 wherein the tube 10 is shown schematically in linear form. To simplify the drawing, only three of the usual ten positions or groups of electrodes, numbered "0," "1," and "9," are shown. In the circuit, the cathode 14 is connected to a source of reference potential such 50 as ground. Each spade electrode 16 is connected through a spade load resistor 26 to a common spade buss 28. The spade buss 28, in turn, is coupled through a common spade load resistor 30 to a positive supply voltage of about 200 volts. This arrangement provides a bias voltage of about 100 volts on the spade buss. Each target electrode 18 is coupled through a load resistor 38 to a common target buss 40 which is coupled, in turn, to the positive 200 volt supply voltage.

55 The switching electrodes 20 which are employed to switch an electron beam from position to position within the tube 10 may be connected in any one of a number of suitable ways to provide the desired switching operation. According to one suitable arrangement as shown, the switching electrodes are connected in two sets, with alternate electrodes being connected together to form a set. The two sets of switching electrodes are 60 coupled to a suitable source of switching pulses such 65 as a multivibrator. The switching electrodes 20 are connected to the source of switching pulses in such a manner that the potentials of the switching electrodes are 70 alternately increased and decreased to effect the switching operation.

as a bistable multivibrator 42. The output pulses from each side of the multivibrator serve to switch the electron beam from one position to the next.

According to the invention, circuit means are provided for clearing and resetting an electron beam at a desired position within the tube 10. For purposes of illustration, the circuit shown is adapted to clear the tube and reset the beam at the zero position. Of course, any one of the positions may be considered the zero, or reset, position. Essentially, the circuit comprises first means for generating and applying a negative pulse to the spade buss and thus to all of the spades, an operation which causes the tube to clear; and second means for causing the spade at the "0" position to return to its normal operating voltage more slowly than the spades at the other positions. This operation of the "0" spade causes it to carry, for a suitable length of time, the lowest electrical potential of all of the spades, and, as a result, an electron beam forms at the "0" position.

Any suitable pulse generator circuit may be employed for the above-mentioned first means. One suitable circuit employs a thyratron 44, for example a type 5696 thyratron, which includes a cathode 46, a control grid 48, a shield grid 50, and an anode 52. The cathode 46 of the thyratron is connected to ground, and the control grid 48 is coupled through a suitable bias resistor 54 to a negative bias voltage of the order of 15 volts. The control grid is also coupled through a capacitor 56 to a suitable source of positive pulses 58. The shield grid 50 is connected to the cathode, and the anode 52 is coupled through a load resistor 60 to the target buss 40 and the 200 volt supply. The anode 52 is also coupled to the spade buss through a differentiating network which includes a capacitor 62 and resistor 30 connected in series between the thyratron anode and the target buss with the junction 64 between them being connected to the spade buss. The junction 64 is also coupled through a resistor 66 and a parallel combination of resistor 68 and capacitor 70 to ground. The second means, above-mentioned, includes at the "0" spade, a diode 72 which is connected across the "0" spade load resistor 26 with its anode connected to the spade and its cathode connected to the spade buss. The diode 72 is thus oriented to provide easy current flow from the buss to the spade. The "0" spade and the anode of the diode are also connected through a capacitor 74 to ground.

In operation of the circuit of Fig. 1, let it be assumed that the tube is counting in normal fashion and an electron beam is being switched from position to position under the influence of pulses applied to the switching electrodes from the multivibrator 42. When it is desired to clear and reset the tube, a positive pulse 58 is applied to the thyratron 44 which fires and produces a negative pulse 76 at the spade buss 28. The negative pulse 76 has an amplitude slightly larger than 100 volts and lowers the spade buss and the spade electrodes in potential to 0 volt or below. The diode 72 serves to rapidly discharge capacitor 74 to the potential of spade buss 28. Capacitor 74 had previously been charged to the potential of the spade buss. Since all of the spade electrodes are at the same potential, the electron beam is cleared from the position in which it was formed and electrons are held in the vicinity of the cathode under the influence of the crossed electric and magnetic fields in the tube. After the pulse 76 has passed, the spade buss returns to its normal operating level of about 100 volts with respect to cathode 14, and all of the spade electrodes return to their normal operating voltages of about 100 volts except the spade in the "0" position. This "0" spade is maintained initially at a reduced voltage of about 0 volt by the discharged capacitor 74, and the rate at which this spade returns to normal operating voltage is determined by the time constant of the network including spade resistor 26 in parallel with the reverse resistance of the diode 72 and capacitor 74. Since the spade at the

"0" position is thus maintained at a lower potential than the other spades for a period of time, the electron beam from the cathode forms on the target at the "0" position under the influence of the spade at this position.

In one typical circuit, the target resistors 38 have a value of about 18,000 ohms; the spade resistors 26 have a value of about 100,000 ohms; and the capacitor 74 has a value of about 100 μ uf. The pulses 32 have a magnitude of about -100 volts and a "rise" time of approximately $1/2$ μ sec. minimum from a low impedance source. The spade supply voltage is about 150 volts, and the target supply voltage is about 200 volts.

What is claimed is:

1. An electron beam clearing and resetting circuit for a multi-position electron beam tube comprising an electron beam tube including an electron emitting cathode and a plurality of groups of electrodes arrayed in electron beam receiving relation with respect to said cathode; each of said groups of electrodes including an electron beam target electrode and a spade electrode adapted to form and hold an electron beam on its associated target electrode; a common spade buss; a spade impedance coupled between each of said spade electrodes and said common spade buss; circuit means connected to said spade buss for changing the potential of the buss and the spade electrodes at a predetermined rate between a positive reference potential and a lower potential; and circuit means coupled to said selected spade electrode for raising the potential thereof from said lower potential to said reference potential at a slower rate than the other of said spade electrodes so that, for a time, the potential of said selected spade is lower than the potentials of the other spades and an electron beam forms on the target electrode associated with said selected spade electrode.

2. A circuit defined in claim 1 wherein said circuit means includes a capacitor and a diode, said diode being connected across the spade resistor of said selected spade.

3. A beam clearing and resetting circuit for an electron beam switching device comprising an electron beam switching tube including an electron emitting cathode and a plurality of groups of electrodes arrayed in electron beam receiving relation with respect to said cathode; each of said groups of electrodes including an electron beam target electrode and a spade electrode adapted to form and hold an electron beam on its associated target electrode; a spade impedance coupled between each of said spade electrodes and a common spade buss; circuit means connected to said spade buss for changing the potential thereof at a certain rate between a positive operating potential and a lower reference potential; and circuit means coupled to said selected spade electrode for raising the potential thereof from said reference potential to said operating potential at a slower rate than the other of said spade electrodes so that momentarily said selected spade is at a lower potential than the other spades and an electron beam forms on the target electrode associated with said selected spade electrode.

4. The circuit defined in claim 3 wherein said circuit means includes a capacitor coupled between a source of reference potential less positive than said operating and reference potentials and the spade impedance of said selected spade electrode, and a diode connected across said last-named spade impedance.

5. The circuit defined in claim 3 wherein said circuit means comprises a crystal diode connected between the spade impedance of said selected spade electrode and a source of reference potential lower than said operating potential and said lower reference potential.

6. A beam clearing and resetting circuit for an electronic switching device comprising an electron beam switching tube including an electron emitting cathode and a plurality of groups of electrodes arrayed in electron beam receiving relation with respect to said cathode; each of said groups of electrodes including an electron beam

target electrode and a spade electrode adapted to form and hold an electron beam on its associated target electrode; a spade buss; means for applying a positive operating potential to said spade buss and to said spades; a spade impedance coupled between each of said spade electrodes and said common spade buss; a source of negative voltage pulses coupled to said spade buss for applying negative pulses to said spade buss and thereby lowering the potential of said buss and said spade electrodes from said operating potential to a lower reference potential; and means for raising the potential of said selected spade electrode from the lower reference potential to said operating potential at a slower rate than the other of said spade electrodes when a negative pulse is not present at said spade buss so that said selected spade electrode is momentarily at least at a lower potential than the other of said spade electrodes and an electron beam forms on the target electrode associated with said selected spade electrode.

7. A beam clearing and resetting circuit for an elec- 20

tron beam switching device comprising an electron beam switching tube including an electron emitting cathode and a plurality of groups of electrodes arrayed in electron beam receiving relation with respect to said cathode; 5 each of said groups of electrodes including an electron beam target electrode and a spade electrode adapted to form and hold an electron beam on its associated target electrode; a common spade buss to which each of said spades is connected; separate sources of high and low reference potentials coupled to said spade buss; and time delay means coupled to a selected one of said spades for raising said selected spade from said low reference potential to said high reference potential at a slower rate than the other of said spade electrodes are raised 15 so that said selected spade has at least momentarily a lower potential than the other spades and an electron beam forms on the target electrode associated with said selected spade electrode.
